Des. 213,504
Patented Mar. 11, 1969

213,504

DOUBLE TOWER PLAYGROUND APPARATUS

Robert S. Wormser, Hillsdale, Mich., assignor to Game-Time, Inc., Litchfield, Mich., a corporation of Michigan

Filed Mar. 4, 1968, Ser. No. 10,839

Term of patent 14 years

U.S. Cl. D34—5
Int. Cl. D21—03

FIG. 4

FIG. 2

FIG. 3

FIG. 1 is an elevational view of the left side of double tower playground apparatus in accord with my design, the right side being similar thereto,

FIG. 2 is a front elevation view of the playground apparatus of the invention,

FIG. 3 is a rear elevational view, and

FIG. 4 is a top plan view of my new design.

The dominate parts of my design are shown in full lines. I claim:

The ornamental design for a double tower playground apparatus, substantially as shown and described.
